INTERCHANGEABLE POST CONSTRUCTION FOR DERRICKS

Filed Jan. 29, 1929

INVENTOR:
LESLIE A. RAWSON,
By
Leslie A. Rawson

ATTORNEY.

UNITED STATES PATENT OFFICE

LESLIE A. RAWSON, OF LOS ANGELES, CALIFORNIA, ASSIGNOR TO EMSCO-DERRICK & EQUIPMENT COMPANY, OF LOS ANGELES, CALIFORNIA, A CORPORATION OF CALIFORNIA

INTERCHANGEABLE POST CONSTRUCTION FOR DERRICKS

Application filed January 29, 1929. Serial No. 335,806.

My invention relates to means for connecting parts together, and in its broad conception it consists of connecting means for rigidly connecting one part to another and which may be loosened so that the parts may be slid relatively without requiring the parts or the connecting means to be displaced.

One use for my invention is on derricks such as are used in the oil-producing industry. 10 As a part of derrick equipment it is necessary to have draw-works, a calf-wheel and a bull-wheel. These wheels are mounted on different sides of the derrick floor and are supported on vertical posts which are connected to the base of the derrick and to a horizontal girt, which is connected to adjacent derrick legs. Ordinarily the posts for supporting the various apparatus just mentioned are secured in place by bolts which extend through 20 openings in the posts and in members of the derrick.

One of the objects of this invention is to provide a means for securing the post to a derrick so that the post may be adjusted horizontally without requiring the parts of the connecting means or the post to be removed from place and without requiring holes to be drilled in the derrick parts.

Another object of this invention is to provide a connecting means of this character having a novel form of attachment member.

Another object of my invention is to provide a combination in which a horizontal member having a flange and a vertical member are secured together by a means which includes an attachment-member having jaws adapted to receive between them the flange and means connecting the attachment-member to the vertical member.

Another object of the invention is to provide a combination as mentioned in which the jaws are angularly disposed to provide a wedge-shaped opening to receive the flange.

It is a still further object of my invention to provide a combination as mentioned in which one of the jaws of the attachment-member is provided with teeth for preventing sideward movement on the flange of the horizontal member.

A further object of the invention is to pro-

vide a combination of this character in which the means for connecting the attachment-member to the vertical member is in the form of a bolt which engages one surface of the flange of the horizontal member.

55

Other objects and advantages of my invention will be pointed out in the ensuing description.

The invention may be better understood by reference to the accompanying drawings, in 60 which—

Fig. 1 is an elevational view showing the utility of my invention.

Fig. 2 is an enlarged perspective view showing the attachment-means of the invention.

65

Fig. 3 is a perspective view of one form of attachment-member of my invention.

Fig. 4 is a perspective view of another form of attachment-member of my invention.

60

Referring to the drawings in detail and 70 particularly to Fig. 1, the numeral 11 represents a post, which is secured to parts 12 and 13 by attachment-means 14 embodying the features of this invention.

For the purpose of explaining the details 75 of the invention, the attachment at the upper end of the post 11 will be referred to. Secured to the post 11 and extending upward therefrom is a guide means 15 for the post which comprises a pair of angles 15^a secured 80 to opposite sides of a web 16 by rivets 17. The angles 15^a have legs 18 which extend outwardly from the web 16 in a plane substantially at right angles thereto. The legs 18 of the angles 15^a are adapted to engage one 85 edge of the part 13. The part 13 in the form of the invention illustrated is in the form of an I-beam having horizontal flanges 20 and a vertical web 21. The legs 18 are adapted to engage adjacent edges of the flanges 20.

90

The connecting means of my invention includes, as an important part thereof, an attachment-member 23, which is illustrated in perspective in Fig. 3. The attachment-member 23 has an upper jaw 24 having a substantially flat and horizontal lower face 25, and has a lower jaw 26, which is angularly disposed with respect to the jaw 24, so as to provide a wedge-shaped mouth or opening 27. The lower jaw 26 is shown as being provided 100

95

with teeth 28, which extend from the front to the rear part of the lower jaw. If desired, however, the teeth may be provided on the flat face 25 of the upper jaw 24, and in addition to this, grooves may be provided in a direction at right angles to the teeth 28 so that the action of the teeth will be to prevent movement of the attachment-member in any direction, after it has been installed. Extending 5 outward from the rearward part of the attachment-member 23 in opposite directions are ears 30 having openings 31 formed therethrough. The openings 31 are formed so that the lowest part thereof rests in substantially the same plane as the lower flat face 25 of the jaw 24. It will be seen from Fig. 3 that the ears 30 extend outward from the upper part of the attachment-member.

The attachment-member 23 is installed as 10 illustrated in Figs. 1 and 2. The attachment-member is placed so that the flange 20 is received by the wedge-shaped mouth 27. The flat face 25 engages an upper flat face 32 of the flange 20 and the teeth 28 of the lower jaw 26 engage a lower face 33 of the flange. There is 15 a attachment-member 23 placed on both the upper and lower flanges 20. Provided for connecting the attachment-member to the angles 15^a to form a part of the post 11 are 20 bolts 34. The bolts 34 extend through openings 35 formed in the legs 18 of the angles 15^a and through the openings 31 of the ears 30. Nuts 36 are secured onto the ends thereof and serve the purpose of pulling the legs 18 25 against the part 13 and of pulling the attachment-members onto the flanges 20. When the parts are securely fastened the attachment-members 23 immovably grip the part 13 and it is impossible for the post to 30 accidentally shift. An adjustment of the post may be readily accomplished, however, by loosening the bolts 34 and moving the attachment-members outward so that they release their grip on the edges of the flanges 20 35 of the part 13 or the part 12.

The important part of this form of the invention resides in the particular design of the attachment-member 23 adapting it to manufacture and sale as a new article of 40 manufacture and its function in the combination.

In Fig. 4 I show an alternative form of the invention, in which an attachment-member 50 is provided with sections 51 connected together by a partition 52 having an opening 53 formed therein. The sections 51 have upper jaws 55 and lower jaws 56 which form wedge-shaped mouths 57. The construction of each section 51 is like that of the upper and lower jaws 23 and 26 of the form of the invention illustrated in Fig. 3, with the exception that they may be narrower. The opening 53 is arranged so that its lowest part is in the same plane as the lower faces of the 55 upper jaws 55. This form of the invention

requires but one bolt, which extends between the sections 50 and 51.

The form of the invention shown in Fig. 4 is a practical form of the invention and further illustrates that the invention is susceptible of modification and that such modifications come within the conception of this invention. 70

I claim as my invention:

1. In combination: a horizontal member 75 having a flange; a vertical member adapted for adjustable connection to said horizontal member; an attachment-member having jaws adapted to receive between them said flange; means connecting said attachment member to said vertical member; and means on said vertical member for guiding the same when it is adjusted on said horizontal member. 80

2. In combination: a horizontal member having a flange; a vertical member adapted to be adjustably secured to said horizontal member; an attachment-member having jaws adapted to receive between them said flange; a bolt connecting said attachment-member to said vertical member; and means on said vertical member adapted for engagement with said horizontal member for guiding said vertical member when it is adjusted on said horizontal member. 90

3. A combination as described in claim 2 95 wherein said bolt is attached to said guide means.

4. A combination as described in claim 2 wherein said bolt extends through and is connected to said guide means. 100

5. A combination as described in claim 1 wherein said guide means limits the movement of said vertical member in one direction. 105

6. A combination as described in claim 1 wherein said guide means acts as a stop to limit the movement of said vertical member in a single lateral direction. 110

7. A combination as described in claim 2 wherein said guide means limits the movement of said vertical member in a single direction. 115

8. A combination as described in claim 2 wherein said guide means comprises a pair of angle plates connected to said vertical member and engages a part of said horizontal member. 120

9. A combination as described in claim 2 wherein said guide means comprises an angle member connected to said vertical member and to said horizontal member. 125

10. A combination as described in claim 1 wherein said guide means is connected to said vertical member and to said means connecting said attachment-member to said horizontal member. 130

11. A combination as described in claim 2 wherein said guide means is connected to said vertical member and to said bolt connecting said attachment-member to said horizontal member. 135

12. As a new article of manufacture, a device for connecting derrick parts together, constructed as a unit of metal and comprising a plate-like body having upper and lower jaws defining a wedge shaped opening at one side thereof, and ears extending outward from the upper part of said body having openings formed therein.

13. As a new article of manufacture, a device for connecting together derrick parts comprising a plate-like body having upper and lower jaws defining a wedge shaped opening at one side thereof, the surface of one of said jaws being flat and the other jaw being angularly disposed and provided with serrations, and ears extending outward from said body having openings extending in substantially the same plane as the surface of one of said jaws.

14. As a new article of manufacture, a device for connecting derrick construction comprising a plate-like body having jaw sections connected together by a partition, the upper surface of each of said jaw sections being flat and the lower surface of each lower jaw section being angularly disposed and provided with teeth, and said partition having an opening formed therein which extends in substantially the same plane as the flat surfaces of said jaws.

In testimony whereof, I have hereunto set my hand at Los Angeles, California, this 23 day of January, 1929.

LESLIE A. RAWSON.
